[57] CLAIM

The ornamental design for a chair, substantially as
shown and described.

DESCRIPTION

FIG. 1 is a side elevational view of a chair showing my
new design with the opposite side being a mirror image
of the side shown;

FIG. 2 is a front elevational view thereof;

FIG. 3 is a top plan view thereof;

FIG. 4 is a rear elevational view thereof;

FIG. 5 is a side elevational view of a modified form of
the chair shown in FIGS. 1-4;

FIG. 6 is a front elevational view;

FIG. 7 is a top plan view; and

FIG. 8 is a rear elevational view thereof.
